PUMP

Joseph B. Brennan, Cleveland, Ohio

Application September 25, 1941, Serial No. 412,300

2 Claims. (Cl. 103—138)

This invention relates as indicated to pumps and more particularly to the type of pump wherein a rotor provided with reciprocable vanes rotates within a bore, so formed that the vanes at opposite ends have engagement with the inner periphery of the bore for substantially all positions of the rotor.

It is a common characteristic of pumps of the general character to which this invention relates that the bore within which the rotor is mounted has a curved surface made up of two concentric arcs of different radii, such arcs being joined by means of special curves of various forms.

Mounted in the bore is a cylindrical rotor, the axis of which coincides with the center of the two concentric arcs of different radii aforesaid. In the prior art constructions, the radius of the rotor has been such as to be substantially equal to the radius of the smaller of the aforesaid arcs of the bore, so that the rotor has a running fit with the smaller of the two arcs which defines a portion of the internal curve of the bore. Vanes, variously arranged as to position and movement in the bore and extending diametrically there-across, serve as the means whereby fluid is transported from one side of the rotor to the other, such vanes, in their extended positions, spanning the space between the periphery of the rotor and the larger of the two concentric arcs aforesaid.

It is a principal object of my invention to provide a pump structure of the character described, but modified as to certain particulars so as to not only improve the functional characteristics of the pump, but to also materially lengthen the life of the pump by substantially reducing the wear to which the same is subjected.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a sectional view of one form of vane pump showing an embodiment of my invention; and

Fig. 2 is a transverse sectional view of the structure illustrated in Fig. 1, taken on a plane substantially indicated by the line 2—2.

Referring now more specifically to the drawing, and more especially to Fig. 1, it will be observed that the pump comprises a housing generally indicated at 1, having an inlet opening 2, and a discharge opening 3. Centrally of the body 1 there is provided a cylindrical opening 4, into which is press-fitted a stator 5, the outer periphery of which is cylindrical to conform to the cylindrical opening 4 receiving the same.

Rotatably supported in the housing 1, and within the stator 5, is a rotor 6 carrying a plurality of diametrically arranged vanes 6a in a manner conventional in the art.

The inner periphery of the stator 5 is divided into four parts—an area generally indicated at 7 which is cylindrical; an area indicated at 8 which is likewise cylindrical; and areas 9 and 10 which are a variation from a true arc, these being generally a limacon curve or variations thereof, about which this invention is not concerned. The curves 9 and 10 are such that when solid diametrically arranged vanes are carried by the rotor, the opposite ends of each such vane will be at all times in substantial contact with the curves 9 and 10. The center of the rotor is indicated at 11. This point 11 is also the center of the arc 7, as well as the arc 8, although the radius of the arc 7 is substantially shorter than the radius of the arc 8.

Fig. 2 is a broken sectional view of Fig. 1, and similar reference characters have been applied thereto to denote like parts, and from the foregoing description, it is believed that the principal features of the pump will be readily understandable to those skilled in the art.

The improvement about which this invention is concerned is the relative proportions of the radius of the rotor with respect to the radius of the smaller arc 7. Heretofore, pumps have been constructed with the radius of the rotor substantially equal with the radius of the arc 7 so as to provide a running fit between the rotor and such smaller curved surface.

In accordance with my invention, the radius 45 of the smaller arc 7 is always substantially greater than the radius of the rotor of the pump, providing a substantial clearance between the rotor and the stator in such area. Of course, the capacity of the pump, which would, according to the prior art, be roughly the volume between the rotor and the stator opposite the large arc 8 times the revolutions per minute of the rotor, is reduced by the amount of the volume in the space between the rotor and the smaller curve 7 times the number of revolutions per minute of

the rotor. This is not a serious handicap since it is convenient, in providing a pump of given capacity, to slightly increase the radii of the curves 7 and 8 to compensate for this difference.

The clearance, or more accurately the space of substantial proportions between the rotor and the smaller arc 7 has a number of advantages, certain of which may be enumerated as follows:

Most commercial materials adapted to be handled by pumps of this character, such as for example a fuel for internal combustion engines, occasionally contain small amounts of entrained foreign matter which have a tendency to be carried around by the rotor blades and lodge in the space between the rotor and the smaller arc or curve of the stator. When a running fit is provided between the rotor and stator in this area, such foreign material destroys the running fit and impairs the function of the pump in destroying this running fit, and even on occasion varies the capacity of the pump slightly.

Still another, and even more important function of this clearance between the rotor and stator, is to avoid certain difficulties experienced in the prior art pumps in their use of vanes with curved ends. From an inspection of Fig. 1, it will be observed that upon counter-clockwise rotation of the rotor, the rear edge of the vane has a tendency to ride on the expanding curve 10, and the forward edge of the vane has a tendency to ride on the contracting curve 9.

In order to reduce the rate of wear, and for other reasons well-known to those familiar with the art, the bore-contacting ends of the vane have been made curved in the manner illustrated in Fig. 1. Now in the prior art constructions where a running fit has been maintained between the rotor and the small arc of the bore, this has required full retraction of the vane into the body of the bore, leaving a small pocket in the end of the vane slot or opening in the rotor which is not completely filled by the vane because of the relieved corners of the vane. This pocket is filled with the material being handled by the pump, and when a relatively volatile material, such as gasoline, is thus handled, the same, due to an actual pinching and binding thereof in these small pockets, has had a tendency to volatilize and give rise to objectionable difficulties in the handling of such material.

When a substantial distance or space is maintained between the stator and the rotor in the area of the small arc of the bore, and for my purposes this space is always greater than the extent to which the ends of the blades are relieved in providing the curved ends on the blades, there is never any trapping of the fuel in small pockets which has heretofore led to the pinching and binding aforesaid.

A pump constructed in accordance with my invention is, therefore, much freer running than the pumps of the prior art; is less apt to deteriorate on account of wear, due to the inclusion of entrained foreign particles in the material being handled by the pump; and produces a smoother flow with a lesser tendency toward the setting up of pulsations on the discharge side than the similar pumps of the prior art. Other

advantages incidental to my improved construction will be apparent to those familiar with the art.

I have not attempted to describe in detail those portions of the pump structure illustrated which are not a part of my invention. The general form of pump which has been illustrated for the purpose of showing the application of one form of my invention will be recognized as corresponding in general to the pump illustrated and described in Curtis Patent No. 2,165,963 to which reference may be had for a more detailed description of the arrangement and mode of operation of the parts in general.

The present improvement is concerned not with the number of vanes employed in the pump, nor the precise curve utilized for connecting the two concentric cylindrical surfaces of the bore body, since my invention is applicable in general to rotary pumps having this general arrangement of working parts.

Other modes of applying the principle of the invention may be employed, change being made as regards the details described, provided the features stated in any of the following claims or the equivalent of such be employed.

I therefore particularly point out and distinctly claim as my invention:

1. In a pump of the character described, the combination of a pump body having a bore, the normal cross-section of which is defined by two concentric arcs of unequal radii, with vane extending and retracting curves joining adjacent ends of said arcs, a substantially cylindrical rotor mounted concentrically with said arcs, vanes slidably carried by said rotor and in engagement at all times at their opposite terminal portions with the inner periphery of said bore, said bore engaging terminal portions of said vanes being arcuately relieved from substantially the center plane thereof to the opposite sides thereof, said pump being characterized in that the radius of said rotor is substantially less than the radius of the smaller of said concentric arcs by an amount at least as great as the radial extent by which said vanes are relieved.

2. In a pump of the character described, the combination of a pump body having a bore, the normal cross-section of which is defined by two concentric arcs of unequal radii, with vane extending and retracting curves joining adjacent ends of said arcs, a substantially cylindrical rotor mounted concentrically with said arcs, vanes slidably carried by said rotor and in engagement at all times at their opposite terminal portions with the inner periphery of said bore, said bore engaging terminal portions of each of said vanes being so proportioned, with respect to the smaller chamber arc, that each of said vanes projects at all times beyond the surface of the rotor and no pocket is formed between the sides of the vane and the sides of its slot while said vane is in contact with and passing across said smaller arc, said pump being characterized in that the radius of said rotor is substantially less than the radius of the smaller of said concentric arcs.

JOSEPH B. BRENNAN.
